SMOKING PIPE

Peter P. Catalano, Joseph P. Catalano, and Frank P. Catalano, North Collins, N. Y., assignors to Panepinto Mfg. Corp., North Collins, N. Y., a corporation of New York

Application February 21, 1947, Serial No. 730,068

1 Claim. (Cl. 131—184)

1

This invention relates to an improved smoking pipe.

It is an object of this invention to provide an improved pipe of the kind to be more specifically described hereinafter, having a removable bowl which may be readily removed from the pipe for cleaning and which may be readily reinstalled.

Another object of this invention is to provide an improved pipe of this kind wherein the smoke passage through the stem extends downwardly and rearwardly from the bowl of the pipe so the smoke is taken from the upper end of the bowl, thus excluding moisture and tobacco from the stem and from the mouth of the smoker.

Still another object of this invention is to provide a pipe having a baffle fixed in the bowl below the removable bowl or lining under which the smoke from the burning tobacco must pass before entering the pipe stem, the baffle providing also a pair of communicating moisture traps, one on each side, and a seat on the top for the removable bowl. The removable bowl is formed with but a single opening on the bottom which will permit the smoke to pass into the front moisture trap on the forward side of the baffle as it leaves the bowl.

A further object of this invention is to provide a rod which is engageable in the smoke passage of the pipe stem and slideable for cleaning the stem. The rod restricts the smoke passage and is formed with a flat lower surface to permit a continuous straight passage between the rod and the passage. The rod is adapted to be frictionally engaged in the stem and may be removed at any time for cleaning the pipe.

With the above and other objects in view, our invention consists in the arrangement, combination and details of construction disclosed in the drawings and specification, and then more particularly pointed out in the appended claim.

In the drawings,

Figure 1 is a top plan view of a pipe constructed according to an embodiment of this invention,

Figure 2 is a longitudinal section taken on the line 2—2 of Figure 1,

Figure 3 is a top plan view, partly broken away, of the pipe with the inner bowl removed,

Figure 4 is an end elevation of the mouthpiece,

Figure 5 is a fragmentary transverse section taken on the line 5—5 of Figure 2,

Figure 6 is a fragmentary section taken on the line 6—6 of Figure 2,

Figure 7 is a fragmentary detailed section of the connection of the cleaning rod.

Referring to the drawing, the numeral 10 designates generally a smoking pipe constructed with a downwardly inclined smoke passage 11

whereby the moisture from the pipe will not be conveyed to the mouth of the smoker. The pipe 10 is formed with a bowl 12 at the forward end thereof, having a portion of the stem 14 extending from the rear edge thereof. The stem 14 extends from the upper edge of the bowl 12, nearly to the bottom edge thereof, and tapers outwardly from one side of the bowl.

The smoke passage 11 is formed in the stem 14 adjacent the upper edge thereof, communicating with the space in the bowl at the upper end so that the lower end of the bowl provides a moisture trap. The upper end of the stem 14 is downwardly and outwardly inclined parallel to the passage 11, and the lower surface of the stem is substantially parallel to the lower surface of the bowl 12.

A downwardly and inwardly inclined passage or recess 15 is formed at the front end of the stem 14, which provides communication between the forward end of the smoke passage 11 and the lower end of the bowl 12. A transverse baffle 16 is fixed or formed in the bowl 12, having the lower edge thereof spaced upwardly from the bottom of the bowl whereby the bowl 12 is formed into a pair of moisture chambers 17 and 18, connected by a passage 19 below the baffle 16. The upper end of the baffle 16 is flat, against which the bottom 20 of the removable inner bowl or lining 21 is adapted to abut. The inner bowl or lining 21 is threadably engaged as at 22, to the inside of the bowl 12, and is formed at its upper end with an outwardly extending annular flange 24.

The flange 24 is knurled about its periphery to provide for the easy removal and insertion of the lining 21. The lining 21 is substantially closed about its sides and bottom and the smoke from tobacco burning in this lining will pass through a single opening 25 in the bottom wall 20. The opening 25 is formed in the wall 20 in such a manner that when the lining 21 is securely disposed in the bowl 12, the opening 25 will be at the forward end of the pipe and the smoke from the lining will first pass into the forward moisture chamber 17. The smoke will then pass through the passage 19 into the second or rear chamber 18, upwardly through the passage 15 and then through the smoke passage 11.

A more or less conventional mouthpiece 26 is adapted to be secured to the rear end of the stem 14. In addition to having a pipe formed in this manner whereby the smoke must pass upwardly from the bowl before going through the smoke passage to the mouth of the smoker, we have provided a cleaning rod 30 which is to be a part of

the pipe and which may be used at any time for cleaning the smoke passage 11. The rod 30 may also be used for securing the mouthpiece 26 to the stem 14 where the abutting edges of the mouthpiece and stem are flat and no other means is provided for securing the mouthpiece to the stem.

The cleaning rod 30 is formed of an elongated rod 31, substantially cylindrical in shape, having a flat surface 32 on one side thereof. The flat surface 32 extends throughout the entire length of the rod 31. The rod 30 is adapted to be engaged in the smoke passage 11 and will substantially fill the passage 11, as shown in Figure 6, leaving a restricted passage 34 below the flat surface 32. The close fit of the rod 30 in the smoke passage 11 will retain the rod in the pipe. The shape of the rod 30 as seen in Figure 6, is maintained throughout the major length and will extend to the forward end of the smoke passage 11 where the smoke passage 11 communicates with the vertically inclined passage 15.

A reduced diameter lug or pin 35 is formed on or fixed to the forward end of the rod 31 and a frusto-conical cleaning head 36 is fixed on the forward end of the pin 35. The widest or divergent end of the cleaning head 36 is disposed rearwardly and the converging end of the cleaning head is at the forward end of the cleaning rod 30. The diameter of the cleaning head 36 is complete and will be substantially the same as the smoke passage 11.

When the cleaning rod 30 is in position in the pipe 10, the cleaning head 36 will be disposed between the inner lining 21 and the forward side of the passage 15 to permit the free passage of smoke from the passage 15 into the restricted smoke passage 34. At the rear end of the rod 30 there are provided a pair of outwardly extending arms or lugs 37 forming a head, which lugs are adapted to be engaged in an opening or recess 38 in the rear end of the mouthpiece 26 so that the rod 30 will be restricted in its forward movement in the pipe. The end of the rod 30 adjacent the arms 37 is of a smaller cross section and the flat side 32 is inclined upwardly as indicated at 45 so that the bar 39 forming the lugs 37 will be spaced upwardly from the bottom of the smoke passage 11 to provide an enlarged opening at the mouthpiece.

The rod 30 may also be formed in two pieces as 40 and 41, connected together intermediate the length of the rod 30, substantially at the point of connection between the mouthpiece 26 and the stem 14. One section such as outer section 40 may be provided with a reduced diameter threaded stud 42, engaging in a threaded opening 44 in the adjacent end of the inner abutting rod section 41.

In order to clean passage 11, mouthpiece 26 is separated from stem 14 by a rearward pull and rod 30 will be moved through passage 11 with cleaner head 36 scraping the walls of passage 11. Mouthpiece 26 may be cleaned in either one of two ways. With mouthpiece 26 held in one hand, rod 30 may be pressed rearwardly so as to push head 37 out of recess 38, whereupon head 37 may be grasped between a couple of fingers and rod 30 pulled rearwardly through passage 11 in the mouthpiece so that head 36 will move the gummy material through the rear of the mouthpiece. A better way of cleaning the passage in the mouthpiece is to separate the latter from stem 14, thereby pulling rod section 41 rearwardly. Rod section 41 is then unthreaded from section 40 and the latter is pulled rearwardly

through mouthpiece 26. Rod section 40 is then reversed and inserted into mouthpiece 26 from the forward end of the latter, disposing the threaded end 42 rearwardly. Rod section 41 is then threaded onto section 40 and the coupled rod is then pulled forwardly through mouthpiece 26, thereby pulling the gummy material forwardly by scraping of head 36 in passage 11. The cleaning rod 30 constitutes a coupling for the mouthpiece 26 and stem 14 and is normally disposed in passage 11 during the smoking of the pipe.

We do not mean to confine ourselves to the exact details of construction herein disclosed, but claim all variations falling within the purview of the appended claim.

What we claim is:

A smoking pipe comprising a bowl, a cup-shaped receptacle in said bowl, said receptacle being of a depth less than the depth of said bowl and said receptacle having an opening in the bottom thereof, a stem projecting from said bowl and formed with a longitudinal passage having a circular cross section terminating at its bowl end above the bottom of said receptacle, said bowl having a recess extending from the bowl end of said passage to a point below the bottom of said receptacle, a mouthpiece projecting from said stem and having a passage aligning with said stem passage, said passages inclining upwardly and forwardly, and a cleaner engaging in said passages, said cleaner comprising an elongated rod round in cross section and having a flat lower side spaced from the wall of said passages and forming a lower restricted smoke passage, a frusto-conical cleaner head at the forward end of said rod, a small diameter shank connecting said head with said rod, said small diameter shank and cleaner head being normally positioned within the bowl recess when the pipe is being smoked, said mouthpiece having a recess at its rear end extending laterally of the opposite sides of the mouthpiece passage, and a head fixed to the rear end of said rod engaging in said latter recess.
